(57) **CLAIM**

The ornamental design for billed cap with side glare shielding, as shown and described.

DESCRIPTION

FIG. 1 is a perspective view of a billed cap with side glare shielding according to the present invention;

FIG. 2 is a side elevation view thereof;

FIG. 3 is a front elevation view thereof;

FIG. 4 is a rear elevation view thereof;

FIG. 5 is a top plan view thereof; and,

FIG. 6 is a bottom plan view thereof.

The wearer's head depicted in long-short-short broken lines in FIG. 2 illustrates environmental matter, and forms no part of the claimed design. The broken lines shown with uniform segments along the seams and edges of the crown of the claimed design are stitching, and form no part of the claimed design.

The cross-hatching that occurs intermittently on the crown of the claimed design represents a woven texture, and is understood to extend across the entirety of the surface upon which it occurs. The stippling on the size adjustment strap represents hook-and-loop fastening.
